(57) **CLAIM**

The ornamental design for a body of dry cleaning machine, as shown and described.

DESCRIPTION

FIG. 1 is a perspective view of a body of dry cleaning machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof with the addition of a partial view of interior clothes hangers in broken lines and the addition of a door shown in broken lines;

FIG. 9 is a front view of FIG. 8;

FIG. 10 is a perspective view thereof shown during operation with the door closed and interior light lit; and,

FIG. 11 is a cross-sectional view along line 11-11 of FIG. 8 showing the interior side thereof, and with the lower pull out drawer removed.

The broken line showing of interior details in FIGS. 8-11 and a door in FIGS. 8-10 is included for the purpose of showing environmental portions of the body of dry cleaning machine and forms no part of the claimed design.
